UNITED STATES PATENT OFFICE

HUGO MAASHOFF, OF NEW HAVEN, CONNECTICUT, ASSIGNOR TO THE GREIST MANUFACTURING COMPANY, OF NEW HAVEN, CONNECTICUT, A CORPORATION OF CONNECTICUT

SEWING MACHINE TUCK MARKER

Application filed February 21, 1930. Serial No. 430,277.

This invention relates to a sewing machine tuck creaser or marker consisting mainly of only a few sheet metal parts which can be formed by stamping, thus affording an inexpensive construction. To this end the frame of the device consists of a presser foot part adapted to be attached to the presser bar of a sewing machine and which has, integral therewith, a laterally extending plate 10 which in turn has an integral forwardly extending part supporting an integral upturned standard member to which an operating lever is pivotally attached. Overlying the laterally extending plate, just referred to, is an adjustable gage plate superimposed on which is a transverse clamping plate attached by a set screw to the said laterally extending plate or at the junction of the said plate with said forwardly extending part. 15 The marking or creasing member consists of a spring sheet metal device in the form of a loop, the two parts of the said marking or creasing device being constructed near their free ends in a well known manner for creasing or marking a fabric passing between them. The lower arm or part of the said creasing or marking device is arranged to pass beneath the said clamping plate so that the latter serves to secure said creasing or 20 marking device and said gage plate in place. The operating lever, which is pivoted to the frame part above referred to, impinges against the upper arm of said creasing member and is lifted, after each downward stroke 25 imparted thereto by a projection carried by the needle bar of the sewing machine, by the upwardly springing part of said creasing member.

In the accompanying drawings Fig. 1 is a plan view of the improved attachment; Fig. 2 is a front view thereof; Fig. 3 is an end view looking from the left of Figs. 1 and 2; Fig. 4 is a detail plan view of the frame of the attachment; Fig. 5 is a detail view of the gage plate; Fig. 6 is a detail bottom view of the clamping plate; Fig. 7 is a section on line 7-7, Fig. 1.

Referring to the drawings, 12 denotes a presser foot having a shank 13 adapted for attachment to the presser bar of a sewing

machine. Formed integral with said presser foot, and extending laterally therefrom, is a plate 14 having at its end an integral forwardly extending part 15 integral with which is an upwardly extending standard or 55 arm 16 the end of which is turned forward to form a lug 17 to which the operating lever 18 is pivoted. These integral parts 12, 13, 14, 15, 16 and 17, constitute the frame of the attachment.

Overlying the said laterally extending plate 14 is a gage plate 19 superimposed on which is a transverse clamping plate 20 which is secured to the frame by set screw 21.

The creasing member 22 is in the form of a spring sheet metal loop the lower and upper arms of which are constructed, respectively, with an upturned lug 22^a and a groove 23 registering with the said lug 22^a. This creasing member is of well-known construction and operates in the usual manner to form a crease on a layer of fabric passing over said lug and beneath said groove. The lower arm of this creasing member, which is of spring sheet metal, underlies the said clamping plate 20, so that the latter serves to secure said creasing member as well as said gage plate in any positions to which these parts may be adjusted.

The gage plate 19 is provided near one end with a forward extension 19^b having upturned lugs 19^a at its forward edge and which lugs embrace the lower arm or part of the creasing member; and the clamping plate 20 is provided with downturned lugs 20^a which embrace said lower arm of said creasing member and which also embrace said forwardly extending part 15 of the frame of the attachment. The upturned lugs 19^a on the gage-plate 19 serve as a guide for the folded edge of the fabric being stitched, the adjustment of the gage plate 19, on which said lugs are formed, determining the width of the tuck being formed. One of the lugs 19^a is provided with a horizontal extension 19^c which overlies and smoothes out or presses down the folded fabric passing beneath it, thus doing away with the smoothing-out 100

plates heretofore in use in some tuck-creasing attachments.

The upward movements of the operating lever 18, under the influence of the spring upper arm of the creasing member, are limited by a lug 24^a overlying the upper edge of said operating lever and carried by a stop plate 24 secured in place by a rivet 27 passing through the lug 17 and on which rivet said operating lever is pivoted. Said stop plate 24 is constructed at its lower end with an inverted lug 24^b received in a notch in the lower edge of the lug 17, so that said stop plate is held stationary by these engaging parts.

From the foregoing it will be understood that the invention provides a sewing machine tuck creasing or marking attachment consisting, aside from the set screw 21 and rivet 27, of only six sheet metal parts, to wit: the frame, the operating lever 18, the gage plate 19, the clamping plate 20, the creasing member 22 and the stop plate 24. These sheet metal parts may obviously be formed in an inexpensive manner by stamping.

Having thus described my invention, I claim and desire to secure by Letters Patent:

1. A sewing machine tuck marker comprising a one-piece sheet-metal frame having a presser foot part adapted for attachment to the presser bar of a sewing machine, an adjustable gage plate having a presser foot part adapted for attachment to the presser bar of a sewing machine, an adjustable gage plate having upturned work-guiding lugs at its forward part, one of said lugs having a two-part marking member in the form of an integral loop, an operating lever for said marking member pivoted to a part of said one-piece frame, a clamping plate 19, the clamping plate 20, the creasing member 22 and the stop plate 24. These sheet metal parts may obviously be formed in an inexpensive manner by stamping.

2. A sewing machine tuck marker consisting mainly of six sheet metal parts including a one-piece frame having a presser foot part adapted for attachment to the presser bar of a sewing machine, an adjustable gage plate, an adjustable spring metal looped marking member, a clamping plate by which said gage plate and marking member may be held in any position to which they may be adjusted, an operating lever for said marking member pivoted to a portion of said frame, and a stop plate for limiting the upward movements of said operating lever.

3. A sewing machine tuck marker comprising a frame having a presser foot part integral with which is a laterally extending part which, in turn, has an integral forwardly extending part provided at its forward end with an upwardly and laterally extending portion having at its end a forwardly extending lug, a gage plate overlying said laterally extending frame part and having a forwardly extending part provided with spaced upturned lugs, a two-part spring creasing member the lower part of which

overlies said forwardly extending frame part and is embraced by said lugs, a clamping plate overlying said forwardly extending frame part, and also overlying the lower part of said creasing member and said gage plate, a set screw for said clamping plate, an operating lever pivoted to said lug and engaging the upper part of said creasing member, and a stop member for limiting the upward movements of the upwardly springing upper part of said creasing member.

4. A sewing machine tuck marker comprising a one-piece sheet metal frame having a presser foot part adapted for attachment to the presser bar of a sewing machine, an adjustable gage plate having upturned work-guiding lugs at its forward part, a spring sheet metal two-part marking member, in the form of an integral loop, an operating lever for said marking member pivoted to a part of said one-piece frame, a clamping plate 19, the clamping plate 20, the creasing member 22 and the stop plate 24. These sheet metal parts may obviously be formed in an inexpensive manner by stamping.

5. A sewing machine tuck marker consisting mainly of six sheet metal parts including a one-piece frame having a presser foot part adapted for attachment to the presser bar of a sewing machine, an adjustable gage plate having upturned work-guiding lugs at its forward part, one of said lugs having a two-part marking member in the form of an integral loop, an operating lever for said marking member pivoted to a part of said one-piece frame, a clamping plate 19, the clamping plate 20, the creasing member 22 and the stop plate 24. These sheet metal parts may obviously be formed in an inexpensive manner by stamping.

In testimony whereof I affix my signature.

HUGO MAASHOFF.
